(57) CLAIM

I claim the ornamental design for combination knife and flashlight, as shown and described.

DESCRIPTION

FIG. 1 is a top front perspective view of a combination knife and flashlight showing my new design;

FIG. 2 is a bottom front perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 left side elevation view thereof; and,

FIG. 8 right side elevation view thereof.

The broken line showing of the blade is provided for purposes of environment and forms no part of the claimed design.
